UNITED STATES PATENT OFFICE.

JOHN L. CREVELING, OF NEW YORK, N. Y., ASSIGNOR TO SAFETY CAR HEATING AND LIGHTING COMPANY, A CORPORATION OF NEW JERSEY.

REVERSIBLE BRUSH-HOLDER FOR USE WITH DYNAMOS.

1,276,727.

Specification of Letters Patent. Patented Aug. 27, 1918.

Application filed December 26, 1911, Serial No. 667,740. Renewed May 28, 1918. Serial No. 237,173.

To all whom it may concern:

Be it known that I, JOHN L. CREVELING, a resident of New York, in the county and State of New York, have invented certain 5 new and useful Improvements in Reversible Brush-Holders for Use with Dynamos, as set forth in the annexed specification and drawing, forming a part thereof.

My invention pertains to that class of 10 dynamos having rotors subject to reversals in direction of rotation and has for its object to produce a dynamo capable of delivering current of constant polarity to line, regardless of such reversals in direction of rotation of the rotor.

Figure 1 is a partial elevation and longitudinal section of a portion of my improved dynamo.

Fig. 2 is a transverse section of my dynamo 20 on the line A—B of Fig. 1. The section shown in Fig. 1 is taken on the line C—D of Fig. 2.

Fig. 3 is a section of one of the brush holders and coöperating mechanism shown in 25 Figs. 1 and 2.

Fig. 4 is a plan and partial section of the supporting means for carrying the brush holders.

Referring to Figs. 1 and 2, 1 represents an 30 armature provided with the commutator 2 and carried by the shaft 3 mounted in suitable bearings carried as by end castings, one of which is indicated at 4. The said end castings are provided with flanged portions 35 5 and are secured to the shell or field frame 6 as by screws 7. The end casting 4 is provided with an extended hub 8 upon which are clamped ring members 9 and 10 which are firmly supported by said hub 8 and insulated therefrom as by an insulating member, or sleeve, 11. The ring member 9 is provided with a suitable binding post 12 by which the same may be connected to an external circuit and the ring member 10 40 is provided with a suitable binding post 13 for a like purpose. This ring member 9, in a four-pole machine, as shown in the drawing for example, is provided with four arms 14 of magnetic material and the ring member 10 is provided with four arms 15 of magnetic material, the said arms being so disposed in pairs with relation to each other that brush holders placed between each pair and rotated in one direction will alter- 45 nately contact with arms carried by alternate 55 ring members in a manner that will herein- after more plainly appear. Between pairs of the arms 14 and 15 there are placed brush holders 16, 17, 18 and 19 each of which carry brushes 20 pressed upon the commuta- 60 tor 2 as by means of any suitable spring mechanism indicated at 21. The brush holders are carried by links 22 insulated there- from and terminating in the rods 23, each having one end carried in such manner as to 65 be free to revolve within the bosses 24 as indicated. The opposite extremities of the rods 23 are provided with depressions into which fit the pins 25 fastened into handles 26 and carried by the bosses 27 in such 70 manner as to be movable laterally therein and are normally held in the position shown in Figs. 1 and 4 as by the springs 28. The brush holders are provided with an iron magnet frame as shown in section at 29 in 75 Fig. 3 which is provided with windings 30 which may be connected in any desired manner to become energized when the generator becomes active as, for example, connected across the armature. The arms 14 and 15 80 and the magnet shell or frame 29 are preferably copper plated to prevent rust and to prevent "freezing" between the magnets 29 and the arms 14 and 15 as will be understood by those skilled in the art. If desired, the 85 brush holders may be provided upon oppo- site sides with hook members 31 insulated therefrom and provided at their extremi- 90 ties with hooks 32. These hooks 32 may then all be joined to mechanically unite the 95 various brush holders to cause their moving in unison by the springs as indicated at 33 or each pair of hooks, save one, may be connected with the links 34 and then a spring used to connect the remaining pair as indi- 100 cated in Fig. 2. The connection between the brush holders by means of the springs and links will, of course, tend to cause the brushes moving downwardly on one side of the commutator to counterbalance the ones moving upwardly on the opposite side there- 105 of and will tend to prevent revolution or swaying of the brush holders around an axis normal to the commutator. With the brush holders united mechanically as indicated in Fig. 2, the magnet windings of the brush holders may be connected as indicated in the said figure—that is, one end of the winding

on the holder 16 may be connected to the insulated hook on the left hand side thereof and the opposite end of the winding to the hook on the right hand side. The winding 5 30 of the brush holder 17 may be connected in a like manner to the hooks on the opposite sides thereof. One winding of the brush holder 18 may be connected to the hook on the right hand side and the remaining terminal 10 of the said winding connected to one of the arms 14. The brush holder 19 may have one of its windings connected to the hook on the upper side thereof and the remaining end connected to one of the arms 15. 15 With this arrangement it will be noted that inasmuch as the hooks are all insulated from their respective supports, the coupling up of the hooks with the links and springs 33 as indicated in Fig. 2 will place the magnet 20 windings of the four brush holders (see Fig. 2) in series with each other and in shunt across the ring members 9 and 10 which in turn are in contact with the brush holders of opposite polarity respectively. If desired 25 that the brushes 20 shall be held, when in their operative positions, radially with respect to the commutator 2, the arms or links 22 may be corrugated as shown at 35 in Fig. 3 or otherwise made slightly flexible and 30 the members or arms 14 and 15 may be so disposed that when the faces of the iron magnet frames 29 are drawn snugly against the same, the links 22 will spring slightly and allow the brushes to assume a radial 35 position.

An operation of my dynamo is substantially as follows:

If the dynamo have its armature 1 rotating in such direction that its uppermost 40 part is moving away from an observer, looking at Fig. 1, and therefore rotating in such direction that the commutator 2 is moving in the direction indicated by the arrow in Fig. 2, the friction of the brushes 20 upon 45 the commutator 2 will cause the brush holders 16 and 18 to move into contact with two of the arms 14 and the brush holders 17 and 19 to move into contact with two of the arms 15 and, therefore, the brushes upon 50 the same diameters will be in electrical communication with arms carried by the same ring member 9 or 10 as is proper in a multi-polar machine as shown. If now the speed of the machine be raised sufficiently that its 55 electro-motive force is appreciable, the energization of the windings 30 will cause the magnetic frames 29 in contact with the magnetic arms 14 and 15 to firmly grip the same and hold the brush holders from vibration or chattering. If now the armature stop, 60 the windings 30 will become deenergized and if the armature be revolved in an opposite direction the friction of the brushes 20 upon the commutator 2 will cause the brush 65 holders 16, 17, 18 and 19 to move into con-

tact with the arms connected in a reverse manner to the ring members 9 and 10 than above mentioned and, therefore, the connection of the brush holders with respect to the ring members 9 and 10, and an external circuit 70 will be reversed in such manner as to compensate for reversals in the direction of rotation of the armature and cause the current delivered to line to remain of the same direction as above in a well-known manner. 75 If now the speed be raised until the electro-motive force of the generator is appreciable, the brush holders will firmly grip the arms 14 and 15 to cause a good electrical communication therewith and by this magnetic grip 80 upon the arms the brush holders will be firmly supported and held free from vibration or chattering, and the links 22 will be relieved of any strain due to rotation of the commutator and any uneven wear thereof. 85 In practice, it is sometimes advisable that the distance traveled by the brush holders upon reversals of direction of rotation should be small and when small enough they may be arranged to move and to be held 90 such manner that the brushes are always normal to a tangent to the commutator. When found advantageous that the brushes, when the generator is in operation, shall be held in a true radial position with regard 95 to the commutator, this may be accomplished by arranging the faces of the members 14 and 15 in planes parallel to the radii upon which it is desired to hold the brushes 20. Then, with this arrangement, the brush 100 holders will first strike the arms 14 and 15 at the portions nearest the commutator and then when the windings 30 become energized the attraction of the same toward the arms 14 and 15 will cause the corrugated links 22 105 shown in Fig. 3 to spring slightly and allow the air gap to be closed and the brush holders held in the position shown in the said Fig. 3 with the brushes in a true radial position with regard to the commutator. If desired 110 at any time to remove one of the brush holders, if the hooks, links and springs 31, 34 and 33 shown in Fig. 2 be not used, it is simply necessary for one to pull the handle 26 belonging to the brush holder to be removed 115 and then the rods 23 will be released and the entire brush box may be readily taken out. If the brush holders be joined as shown in Fig. 2 the spring may be released from its hook and then the necessary links 34 may be 120 unhooked and the brush box desired may be readily removed in a like manner.

From the foregoing it will be noted that I have produced a dynamo which will deliver a uni-directional current to line regardless 125 of direction in rotation of the rotor thereof. Also, that the movable electrical connections necessary to accomplish this purpose are firmly established and held in contact under running conditions and that the brush boxes 130

are mechanically held firmly in their proper positions free from vibration or chattering. It will further be noted that the positions occupied by the brushes may be shifted to

5 accomplish the desired results without supporting the brushes upon any frame or rotating member rotatable about the shaft or axis of revolution of the rotor. It will also be obvious that the brush mechanism in my 10 dynamo is readily removable for inspection or repair and may be readily replaced in the proper operative position.

I make no claim herein to the broad idea of a stop for the brush-holders in combination

15 with additional means for holding the brushes at the point of arrest, nor to the broad idea of magnetic means for holding the brushes under control, as the same are made the subject of my application filed

20 Aug. 7, 1911, Serial No. 642,582. Nor do I make claim herein to electromagnetic means broadly for restraining the brush-holders, as such feature is made the subject of my application filed Aug. 19, 1911, Serial No.

25 644,983. Nor do I claim herein the broad idea of means of securing the brushes together about the commutator, as such feature, in the proper combination, is made the subject of my application filed Sept. 25,

30 1911, Serial No. 651,022. Nor do I claim herein the broad idea of supporting the brush-holding devices on a stationary part of the machine with ability to move relatively to the commutator and into engagement with stops, as the same and other features which are similar and not herein claimed, are made the subject of my application filed Nov. 3, 1911, Serial No. 658,414.

I do not wish in any way to limit myself 40 to the exact details of construction shown in the accompanying drawing nor to the exact mode of operation set forth in this specification, for it will be obvious that wide departure in the way of details may be made 45 without departing from the spirit and scope thereof which is as set forth in the following claims:

1. A dynamo electric machine having an armature and commutator; a brush-holder 50 carrying a brush and capable of automatically assuming two positions, said brush-holder being movable frictionally to either position by the commutator; coöperating means partly* carried by the brush-holder 55 for firmly holding the same in either position; and means for moving the brush-holder so its brush shall be held in true radial position relatively to the commutator in the position assumed by the brush-holder.

60 2. A dynamo electric machine having an armature and commutator brushes and brush holders capable of automatically assuming two positions, said brushes and brush holders being movable frictionally to either 65 position by the commutator; together with

electromagnetic means carried by the brush holders for firmly holding the same in either position.

3. A dynamo electric machine having an armature and commutator brushes and 70 brush holders capable of automatically assuming two positions, said brushes and brush holders being movable frictionally to either position by the commutator; together with stationary means for limiting the movement 75 of the brush holders; and electromagnetic means carried by the brush holders for firmly holding the same in the position last assumed by the rotation of the holders.

4. A dynamo electric machine having an 80 armature, commutator brushes and brush holders capable of automatically assuming two positions dependent upon the direction of rotation of the armature; stationary arms for limiting the movement of the commutator brushes to opposite position, and electromagnetic means carried by the commutator brush holders and operatively connected in circuit with the armature of the machine for firmly holding the brush holders 85 in either position.

5. A dynamo electric machine having an armature, a commutator, and brush-holding devices; means for supporting said devices from a stationary part of the frame and permitting motion of said devices in either of two directions; stationary means for limiting the movement of said brush-holding devices in either direction; and means on the brush-holders for securely holding said devices in 90 accordance with the direction of rotation of the armature. 95

6. A dynamo electric machine having an armature, a commutator, and brush-holding devices; means for pivotally supporting said 100 devices permitting motion thereof in either of two directions, said means including a swinging link; stationary means for limiting the movement of said brush-holding devices in either direction; and magnetic 105 means for securely holding said devices in accordance with the direction of rotation of the armature. 110

7. A dynamo electric machine having an armature, and a commutator; together with 115 a plurality of commutator brushes and brush holding devices adapted to be moved by friction of the brushes with the commutator in either direction through definite arcs; means for pivotally connecting the brush holding devices with a stationary part of the machine, and stationary means connected with the stationary part of the machine for limiting the movement of said brush holders; in combination with means on the brush-holders for securely holding said brush holders at the limit of movement in either direction. 120

8. A dynamo electric machine having an armature, and a commutator; together with 125 a plurality of commutator brushes and

- brush-holding devices adapted to be moved by friction of the brushes with the commutator in either direction through definite arcs; means for supporting the brush-holding devices on a stationary part of the machine; and means connected with a stationary part of the machine for limiting the movement of said brush-holding devices; in combination with electro-magnetic means adapted to be connected in circuit with the armature and to be energized when the said devices reach either limit of movement, for holding said devices from movement.
9. A dynamo electric machine having a commutator, a commutator brush and a brush holder pivotally supported to a stationary part of the machine and adapted to be moved in either of two directions; together with means for stopping said brush holder on rotation of the armature in either direction, and electromagnetic means carried by the brush holder for effectively holding the same no matter in which direction the armature may be rotating.
10. A brush holder for a dynamo electric machine embracing means pivotally supported from a fixed part of the machine and capable of a definite movement in either of two directions in accordance with the direction of rotation of the armature; together with additional means on either side of said holder for limiting the movement thereof, and electromagnetic means carried by the brush holder for firmly magnetically securing the brush carried by the holder in either of two positions of commutation.
11. A brush holder for a dynamo electric machine embracing an electromagnetic winding and a hollow magnetic frame which supports the brush, said frame being pivotally supported from a stationary portion of the machine and adapted to assume either of two angular positions in accordance with the direction of rotation of the armature; together with stationary arms for checking said brush holder when moving in either direction, said stationary arms being constructed of magnetic material adapted to firmly hold the brush holder when it reaches the limit of rotation.
12. A dynamo electric machine comprising an armature and a commutator; a shaft therefor, having a bearing; a pair of rings insulatably secured to the bearing, and each having means for connection to a branch of an outside circuit; each of said rings having a plurality of arms extending axially in proximity to the commutator; each of the arms of one ring being located adjacent an arm of the other ring; and a brush-holder supported between each pair of said adjacent arms, said brush-holders being movable into contact with one or the other of said arms, whereby when the rotation of the commutator reverses, the connection of the brushes is likewise reversed.
13. A brush-holder in combination with a dynamo electric machine; means for pivotally supporting said holder in either of two positions with respect to the commutator of said machine, said means including a swinging link; and means on each side of said holder permanently connected to a fixed part of the machine for limiting the movement of said holder in either direction.
14. A brush-holder comprising a coil-wound elongated casing, and means for supporting the same including a journal-rod, links connected to said rod at each end, and a pivotal connection between the links and casing.
15. A brush-holder comprising a coil-wound casing, and means for supporting the same including a journal-rod, a flexible link, and a pivotal connection between the link and casing.
16. A brush-holder comprising a coil-wound casing having means for supporting a brush, and means for supporting the casing including a flexible link and pivotal support therefor.
17. A brush-holding mechanism comprising a journal support, means for removably mounting a journal in said support, a brush-holder, and means for supporting the latter movably on and relatively to the journal.

JOHN L. CREVELING.
